UNCOILING DEVICE

John Lisy, Cleveland, Ohio, assignor to The American Steel and Wire Company of New Jersey, a corporation of New Jersey

Application July 9, 1942, Serial No. 450,339

4 Claims. (Cl. 242—128)

The present invention relates to improvements in means for uncoiling wire or rod from bundles such as used in the manufacture of various wire products.

One object of the invention is to provide an uncoiling apparatus which will permit the pay off of rod or wire from a bundled coil thereof at a greatly increased speed, as compared to apparatus heretofore used.

A further object is to provide an apparatus for uncoiling rod or wire in a manner which will effectively minimize the likelihood of snarling.

The invention will be fully apparent from the following disclosure, when read in connection with the accompanying drawings, and will be defined with particularity in the appended claims:

In the drawings:

Figure 1 is an end elevation of apparatus embodying the invention;

Figure 2 is a side elevation viewed from the right side of Figure 1;

Figure 3 is a horizontal section on line III—III of Figure 1;

Figure 4 is an enlarged detail section on line IV—IV of Figure 3;

Figure 5 illustrates a modification of the invention; and

Figures 6 and 7 are, respectively, a plan view and a cross section of portions of the uncoiling apparatus shown in Figure 5.

In present-day methods of manufacturing wire products, it is customary to handle the rod from which the wire is ultimately drawn in the form of somewhat loosely coiled bundles of substantially annular form. For many operations in a wire mill it is necessary to coil the rod or wire into relatively loose bundles rather than to wind it on a spool because of the processing to which the rod and wire is subjected, such as pickling, liming, annealing, etc. For this reason various devices have heretofore been used for uncoiling the bundles so as to feed the wire or rod product into various processing machines. The uncoiling devices heretofore in general use are open to the objection that the wire or rod frequently became snarled or tangled, especially when the same is withdrawn from the bundle at a high rate of speed.

The present invention solves a problem which has been before those skilled in the art for many years in a comparatively simple manner by the use of an inexpensively constructed apparatus such as that hereinafter set forth in detail.

The apparatus embodying the present inven-

tion comprises a pair of inwardly inclined platforms 10 and 12 to which are secured respective cylindrical cores 14 and 16 adapted to extend upwardly through the eye or central void of the coiled bundles 18 and 20 of rod or wire stock. Detachably secured to the upper ends of the cores 14 and 16 there are respective coil separator elements 22 and 24. The construction of these separator members is identical; therefore 10 a description of one will suffice for both. Each separator element comprises an inner ring 26 of a diameter sufficient to be easily engaged over the exterior of the core on which it is mounted. Secured to each ring 26 there are a plurality 15 of spokes 28, which extend upwardly and outwardly and connect with a coil separator ring 30 of materially larger diameter than the inner ring 26. Another series of spokes 32 secured to the ring 30 are united near the center to a hub 20 34 adapted to rest on a shoulder 36 formed on a central supporting post 38 which is secured to the inclined base member.

An overhead floating sheave 40 is journaled in a carriage 42 slidably mounted on a pair of 25 inclined guide rods 44 whose lower portions are secured at 46 to a base bracket, as shown. The upper ends of the guide rods are secured at 48 to an overhead structural beam 50 which may conveniently be part of the factory or mill structure in which the apparatus is located. A counterweight 52 is connected by a cable 54 trained around sheaves 56 and attached to the carriage 42 so as to yieldingly normally hold the carriage 42 and sheave 40 in the upper position illustrated 30 in Figure 2. The counterweight normally rests on a fixed support 58, and in this position it holds a switch bar 60 depressed against the action of a spring 62 and closes a circuit across contacts 64 and 66 of circuit wires 68 and 70 which supply current to a motor 72 adapted to drive a suitable piece of processing machinery for using the wire product positioned by the cores 14 and 16. The counterweight 52 may be conveniently guided between the flanges 74 of an upright column 76 forming part of the framework of the factory or mill building structure in which the apparatus is located.

A barrier member 77 formed of converging plates 78 and 80 is secured to the base members 10 and 12 so as to effectively separate the two bundles of rod or wire positioned respectively between cores 14 and 16, this barrier serving to prevent the convolutions of the two bundles from becoming interentangled. It is advantageous to provide the dual bundle supporting means with

the barrier between since this permits the trailing end of one bundle of rod or wire to be welded or otherwise united to the leading end of the other bundle during the time the rod or wire is being uncoiled or paid off from one of the bundles.

In normal operation of the apparatus the separator elements 22 and 24 can be readily removed manually merely by an endwise lifting motion, whereupon the bundles 18 and 20 can be slipped over the cores 14 and 16. The separator elements 22 and 24 are then placed on the cores. The leading end of one bundle of wire, for example, the bundle 20 in Figure 1 is then threaded over the floating sheave 40 and then passed downwardly and around a guide sheave 82 for directing the rod or wire to a machine indicated conventionally at 84, which may be regarded, for example, as a wire drawing machine or wire straightening and cutting machine, both pieces of mechanism being adapted to operate on the rod or wire at a high rate of speed and being effective to withdraw the rod or wire from the bundles at speeds ranging from approximately 1000 to 2500 feet per minute. In uncoiling wire or rod stock from a bundle at such a high rate of speed, the practical difficulty is to prevent snarling or tangling. Practice has demonstrated that the apparatus shown herein permits a high rate of uncoiling, with much less difficulty than that experienced with conventional apparatus heretofore used.

It is considered an important feature of this invention to mount the cores on the inwardly inclined or tapered platforms 10 and 12, such as shown in Figures 1 and 4. Because of this taper or inclination of the supporting platforms a line drawn from the center of the guide sheave 40 through the axis of either core 14 or 16 will be substantially perpendicular to the bundle supporting surface of the platform. This arrangement materially aids in the proper uncoiling of the rod or wire from the bundles, and effectively prevents snarling or tangling of the coils.

The disclosed dual core arrangement automatically positions the bundles so that the coils are withdrawn in the optimum direction over the guide sheave 40. Moreover, the dual arrangement facilitates the welding together of the ends of the coiled bundles and contributes greatly to smooth and efficient operating conditions.

The dot-and-dash center lines in Figure 1 which coincide with the axes of the cores 14 and 16 are perpendicular to the coil supporting surfaces of the platforms 10 and 12, and said center lines intersect at the center of the overhead sheave. Otherwise expressed, the center of the guide groove of the overhead sheave may be said to lie in a plane coincident with the bisector of the angle defined by the extended axial center line of the cores 14 and 16.

The tension applied to the wire or rod beyond the sheave 82 by the wire drawing or other wire processing machine will be transmitted to the bundle and thus gradually uncoil the bundle as the successive convolutions are paid off therefrom. During the uncoiling, the rod or wire will be guided because of the rubbing contact it makes with the outer periphery of the coil separator ring 30. Since this ring is of materially larger diameter than the greatest diameter of the coiled bundle, it will be apparent that as each successive portion of a convolution of the uncoiled wire or rod product travels from the bundle toward the guide sheave 40, it will be forced

outwardly by the camming action of the coil separator ring 30. Thus as each successive convolution is uncoiled it will be effectively loosened, separated and forced outwardly away from the remaining more tightly related convolutions of the bundle. It is regarded important to so arrange the parts as to provide considerable distance between the bundle and the overhead guide sheave, since such spacing will cause the rod or wire to assume an approximately helical form during its pay off.

In the event any tangling or snarling of the product being uncoiled should take place, the resulting excessive tension on the wire will cause the guide sheave 40 and carriage 42 to travel down along the guides 44. Thus an upward pull will be exerted on the counterweight 52. Thereupon the spring 62 will cause the switch to open the circuit across contacts 64 and 66. This will 20 interrupt the operation of the motor 72 which drives the wire drawing or other wire or rod processing machine 84.

Because of the generous head room or distance between the sheave 40 and the floor on which the platforms 10 and 12 rest, it will be understood that on the rare occasions when a snarl occurs the carriage 42 can partake of comparatively long travel without breaking the rod or wire. Such long travel provides a time lag of sufficient duration to permit the processing machine 84 to coast or come to a gradual stop after the power has been automatically cut off by the switch means described. Thus the snarled portion will not reach the machine 84, and an opportunity will be given the operator to remedy the trouble.

In the modification illustrated in Figures 5 through 7, 96 represents a tank or receptacle for holding a body of water in which bundles of rod or wire to be drawn or processed are adapted to be submerged. In this modification the cores 88 are in the form of wooden spoke-like skeleton core elements having a head 90 secured thereto. In this modification each of the coil separator elements is made in the form of a basket-like substantially frusto-conical skeleton frame consisting of an upper circular ring 92 having spokes 94 welded thereto, these spokes also being welded to a lower ring 96 which slips over the exterior of the core member 88. Other spokes 98 are secured at their outer ends to the ring 92 and at their inner ends to a hub 100 which carries a downwardly projecting stud 102 adapted to pass through a bearing opening formed in the member 96 so as to center the separator element with the core. As the wire to be processed is paid off from the core 88, the upper ring 92 of the separator element functions to urge each convolution outwardly as it is uncoiled from the bundle encircling the core 88 so as to thus inhibit the tendency of the convolutions to become entangled.

While I have described quite precisely the design and arrangement of the structure herein illustrated, it is not to be construed that I am strictly limited thereto since various modifications may be made by those skilled in the art without departure from the spirit and scope of the invention as set forth in the appended claims.

I claim:

1. Uncoiling apparatus of the character described comprising a pair of platforms with bundle supporting surfaces inclined downwardly toward one another, respective bundle positioning cores mounted on said platforms, each core carrying a coil separating element comprising an inner annular member engageable with the upper

end of the core and an outer coil separating ring connected to said inner ring, and a barrier located between said cores and adapted to prevent intertwining of the respective bundles carried thereby.

2. An apparatus of the character described comprising a motor adapted to operate a rod or wire processing machine, a supporting platform, a core secured thereto adapted to position a bundle of rod or wire, an overhead sheave about which the rod or wire is trained, a separator element coacting with the core having a coil deflecting portion of a diameter greater than that of the core and effective to separate convolutions of the bundle upon the application of tension on the rod or wire trained over said overhead sheave, a carriage for said sheave slideable along a fixed guide, a counterweight connected by a flexible element with said carriage, a guide pulley over which said flexible element is trained, and a snarl switch normally held closed by the counterweight resting thereon but adapted to be opened when the counterweight is lifted as a result of tension

occasioned by a snarl in the wire, said switch controlling the circuit of said motor.

3. In an apparatus of the character described, a separator element including a lower ring adapted to be engaged with a core having a bundle of rod or wire positioned thereby, an upper ring of a diameter larger than said lower ring, and spokes connecting said rings, said upper ring being adapted to urge the convolutions of the rod or wire outwardly as the same is paid off from said core.

4. In an apparatus of the character described, a separator element including a lower ring adapted to be engaged with a core positioning a bundle of rod or wire, an upper ring of a diameter larger than said lower ring, spokes connecting said rings, said upper ring being adapted to urge the convolutions of the wire outwardly as the same is paid off from said core, and a central hub also connected by spokes to the upper ring, the hub having means adapted to center said rings on said core.

JOHN LISY.
